UNITED STATES PATENT OFFICE.

OTTO HECHT, OF RIDGEWAY, NORTH CAROLINA.

PLOW.

1,259,095.

Specification of Letters Patent. Patented Mar. 12, 1918.

Application filed October 9, 1917. Serial No. 195,620.

To all whom it may concern:

Be it known that I, OTTO HECHT, a citizen of the United States, residing at Ridge-way, in the county of Warren and State of North Carolina, have invented a new and useful Plow, of which the following is a specification.

The device forming the subject matter of this application is a plowing mechanism of that general type in which the plow-carrying vehicle moves backwardly and forwardly along the field to be plowed, without turning the vehicle end for end at the extremities of the furrow, a plow facing in one direction being lowered when the vehicle is moving in one direction, and a plow, facing in the opposite direction, being lowered when the direction of travel of the vehicle is reversed.

It is the object of this invention to provide novel means for raising the respective plows at the ends of the furrows, to provide releasable means for holding the plows elevated and, generally, to improve and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings:—

Figure 1 shows in top plan, a plowing mechanism constructed in accordance with the present invention; Fig. 2 is an elevation disclosing that side of the vehicle upon which the plows are located;

Fig. 3 is an elevation depicting the opposite side of the structure from that shown in Fig. 2, remote parts, such as the plows, being omitted in order that Fig. 3 may show clearly the parts which are undisclosed in detail in Fig. 2;

Fig. 4 is a fragmental side elevation, diagrammatic in nature, and illustrating the mechanism whereby the raising of the plows is effected by the movement of one of the ground wheels, Fig. 4 disclosing some parts which appear in Fig. 3;

Fig. 5 is a transverse section taken through a portion of the frame of the machine, and

illustrating one of the levers shown in Fig. 4, engaged with its keeper;

Fig. 6 is a diagrammatic side elevation illustrating a slight modification in the invention;

Fig. 7 is a rear elevation of the structure shown in Fig. 6, parts being broken away;

Fig. 8 is a side elevation showing one of the wheels with the ring applied thereto;

Fig. 9 is an elevation of the structure shown in Fig. 8, the same being viewed edge-wise.

The device forming the subject matter of this application includes a wheel-mounted vehicle, embodying a frame 1 which may be constructed as desired. Located adjacent one end of the frame 1 is a fork 2 in which is journaled a ground wheel 75. A fork 3 is disposed adjacent the other end of the frame 1 and carries a ground wheel 76. The forks 2 and 3 embody shafts 4 mounted to rotate in the ends of the frame 1, to effect a steering of the vehicle, and the shaft of the fork 2 having a limited endwise vertical movement in the frame, so that the vehicle may accommodate itself readily to inequalities in the ground, the shaft of the rear fork 3 having no such vertical movement, and the frame 1 being supported upon intermediate ground wheels 25 and 26, alluded to briefly at this point, and to be described in detail hereinafter.

A seat 5 is mounted upon the frame 1 near to the fork 3. A standard 6 is erected on the frame 1 at a point adjacent the seat 5, the upper end of the standard being supplied with a bearing 150. Journaled for rotation in the bearing 150 and in a bearing 7 on the frame 1 of the machine is an inclined steering shaft 8, carrying a hand wheel 9 whereby the shaft may be rotated, the wheel being accessible to a person occupying the seat 5. Secured to the lower forward end of the steering shaft 8 is a worm 10 which, as shown in Fig. 3, engages with a worm wheel or segment 11 carried by a shaft 12 journaled in bearings 14 on the frame 1. Secured to the shaft 12 is a depending arm 15. The rear end of a link 16 is pivoted to the lower end of the arm 15, and the forward end of the link is pivoted to the lower end of a lever 17 of the first order, fulcrumed at 18 on the framework of the vehicle. A long link 19 is pivoted at its rear end to the lower end of the lever 17, the forward end of the link being

90

95

100

105

110

pivoted to a laterally offset projection 20 on the fork 2. The forward end of a link 21 is pivoted to the upper end of the lever 17, the rear end of the link being pivoted to an offset projection 22 on the rear fork 3.

The steering operation.—Presupposing that the vehicle frame 1 is supported on the intermediate ground wheels 25 and 26, hereinafore alluded to, it will be understood 10 that when the shaft 8 is rotated by means of the wheel 9, the worm 10, coöperating with the segment 11, will rock the shaft 12, the arm 15 of the shaft actuating the link 16, the link 16 tilting the lever 17 on its fulcrum 18, and motion being imparted to the links 21 and 19, the link 21 rotating the fork 3, and the link 19 rotating the fork 2, the shafts 4 of the forks turning in the frame 1. In this way, the wheels 76 20 and 75 will be turned laterally, in one direction or the other, to effect the steering operation.

Passing to the mounting of the intermediate ground wheels 25 and 26, it may 25 be stated that the side portions of the frame 1 are connected at a point between their ends, by a heavy cross bar 58, sustained by means of braces 59 assembled with the sides of the frame 1. The cross bar 58 includes 30 upstanding side plates 60, shown in Fig. 1 and connected with the sides of the frame 1. The cross bar 58 includes bearings 23 in which a main axle 24 is journaled for rotation. The intermediate ground wheel 35 25 is secured to the axle 24, the intermediate ground wheel 26 being connected with the main axle 24 through the instrumentality of a differential 27, if desired, the differential being indicated diagrammatically 30 in Fig. 1.

A sprocket wheel 28 is connected with the main axle 24, and about the sprocket wheel is trained a sprocket chain 29 engaged with a sprocket wheel 30 carried by 45 a transverse shaft 31 journaled in bearings 32 on the frame 1. The shaft 31 carries a gear wheel 33 meshing into a pinion 34 on a transverse shaft 35 journaled in bearings 36 on the frame 1. The inner end of 50 the shaft 35 carries a relatively large bevelled gear 37 adapted to be engaged by either one of a pair of bevelled pinions 38 attached to the ends of a sleeve 39 which is splined as shown at 43 to a shaft 40 55 driven by an engine 41 and rotatable in bearings 42 on the frame 1, the shaft 40 extending longitudinally of the vehicle. A lever 44 is disposed transversely of the vehicle and is fulcrumed intermediate its ends 60 as shown at 45 on the frame 1. The inner end of the lever 44 is operatively connected as seen at 151 with the sleeve 39, to effect an endwise movement of the sleeve, without interfering with the rotation of the 65 sleeve. The outer end of the lever 44 is

pivoted to a rod 46 extended rearwardly and pivoted to a lever 47 fulcrumed at 48 on the frame of the machine and provided with a latch mechanism 49 adapted to coact with a segment 50 on the frame 1.

70

The propelling and reversing operation.—When the engine shaft 40 is in operation, motion is transmitted by one of the bevelled pinions 38 to the bevelled gear wheel 37 and thence into the shaft 35, the shaft 31 75 being rotated by the coacting gear wheels 34 and 33 on the shafts 35 and 31 respectively. When the shaft 31 is rotated, the sprocket wheel 30 drives the sprocket chain 29 and the latter rotates the main axle 24 80 and the wheels 26 and 25 through the instrumentality of the sprocket wheel 28. When the lever 47 is shifted, the rod 46 is actuated, the latter tilts the lever 44 and the lever 44 moves the sleeve 39 endwise 85 on the shaft 40, thus bringing one or the other of the bevelled pinions 38 into mesh with the bevelled gear wheel 37, thereby to reverse the direction of travel of the vehicle. It will be obvious that when the sleeve 39 90 is positioned as shown in Fig. 1, both of the bevelled pinions 38 are out of engagement with the bevelled gear 37, and then the vehicle is not propelled, even though the engine shaft 40 be rotated.

95

A clutch 51 is interposed in the engine shaft 40 and is controlled by a horizontal lever 52 fulcrumed intermediate its ends, as shown at 152, on the frame of the machine. The outer end of the lever 52 is pivoted to a rod 53, operatively connected with a pedal 54 fulcrumed on the frame 1 and accessible from the seat 5.

100

The starting and stopping operation.—When the pedal 54 is operated, the rod 53 105 tilts the lever 52, the latter shifting the clutch 51, thereby to couple up the engine 41 with the driving shaft 40, and to disconnect the engine therefrom.

Disposed at one side of the main frame 1, as shown in Fig. 1, and located below the main frame, as shown in Fig. 2, is a loop-shaped frame 55. The intermediate ground wheel 25 operates within the contour of the frame 55. The loop-shaped supplemental frame 55 is connected by hangers 56 and braces 57 with one side of the main frame 1. The outer side portion of the loop-shaped frame 55 carries laterally offset bracket 61 and 61^a. The numeral 62 denotes an outer plow beam carrying a plow 66. The plow beam 62 has a transverse head 63, provided with openings 64. A pivot element 65 is mounted in the offset bracket 61^a and may be mounted in any of 120 the openings 64, thereby to permit a raising and lowering, for adjustment, of that end of the plow beam 62 which is remote from the plow 66. The numeral 67 denotes 125 an outer plow beam carrying a plow 72. 130

The plows 72 and 66 point in opposite directions. The outer plow beam 67 is supplied with a transverse head 68 having openings 69. A pivot element 70 is mounted in the laterally offset bracket 61, and may be engaged in any of the openings 69, to permit a vertical adjustment of that end of the plow beam 67 which is remote from the plow 72. The downward swinging movement of the plow beam 67, beyond an extreme point is limited by a stop 71 on the loop-shaped frame 55. The downward swinging movement of the plow beam 62 beyond an extreme point is limited by engagement between the said plow beam and the laterally offset bracket 61.

The numeral 73 marks an inner plow beam, so called because it is located adjacent the inner side of the loop-shaped supplemental frame 55. The beam 73 carries a plow 74 which points in the same direction as the plow 66 and in an opposite direction to the plow 72, the plows 66 and 74 being spaced longitudinally of the machine. The numeral 77 denotes an inner plow beam carrying a plow 78, spaced longitudinally of the machine from the plow 72 and pointing in the same direction as the plow 72, the plow 78 pointing in an opposite direction to the plows 66 and 74. The downward swinging movement of the plow beams 77 and 73, beyond an extreme point, is limited by stops 79 carried by the inner portion of the loop-shaped supplemental frame 55, as indicated in Fig. 1.

It has been pointed out hereinbefore that the ends of the plow beams 62 and 67 may be adjusted vertically, owing to the provision of the heads 68 and 63. This operation can be carried out readily, by the simple mechanisms alluded to, because the beams 67 and 62 are disposed on the outer side of the loop-shaped supplemental frame 55. The plow beams 73 and 77, however, are located adjacent the inner side of the supplemental frame 55 and are more or less inaccessible. A specific means, therefore, is provided for adjusting vertically, the pivoted ends of the plow beams 77 and 73, and this mechanism will now be described.

Vertically spaced horizontally disposed plates or guides 80 are attached to the intermediate cross bar 58. In the guides 80, slide rods 81 and 82 are mounted to reciprocate vertically. The inner plow beam 77 is pivoted as indicated at 83 to the slide rod 82, the inner end of the plow beam 73 being similarly pivoted to the slide rod 81. The lower ends of links 84 are pivoted to the slide rods 81 and 82, the upper ends of the links being pivoted to the lower ends of the levers 85 fulcrumed at 86 on segments 87 carried by the frame 1, the levers 85 being supplied with latch mechanisms 88 which coact with the segments.

The adjustment of the pivoted ends of the plow beams.—It will be obvious that the pivot element 70 may be engaged in any of the openings 69 of the head 68 on the plow beam 67, the pivot element 65 being engaged 70 in any of the openings 64 in the head 63 of the plow beam 62, a vertical adjustment of the pivoted ends of said plow beams being brought about in this way. The levers 85 may be tilted on their fulcra 86, and the 75 links 84 will then raise and lower the slide rods 82, the same operating in the guides 80. When the slide rod 82 is raised and lowered, the pivoted end of the plow beam 77 will be raised and lowered, and when the slide 80 rod 81 is raised and lowered, the pivoted end of the plow beam 73 will participate in the movement.

As shown in Fig. 1, a transverse shaft 89 is located adjacent the seat 5 and is journaled in bearings 90 on the frame 1. Near to one of its ends, the shaft 89 is supplied with an arm 92, connected, as indicated in Fig. 2, by means of a flexible element 94, with the plow beam 73. The shaft 89 is 90 terminally provided with an arm 91, and a flexible element 93 connects the arm 91 with the plow beam 62. The opposite end of the shaft 89 is equipped with a crank arm 95.

A transverse shaft 96 is located adjacent 95 the forward end of the frame 1 and is journaled in bearings 102 on the frame. Adjacent one of its ends, the shaft 96 is provided with an arm 97, connected by means of a flexible element 99 with the plow beam 100 77. The shaft 96 is terminally equipped with an arm 98 united by means of a flexible element 100 with the plow beam 67. At its opposite end, the shaft 96 carries an arm 101, located upon the same side of the frame 105 1 as the arm 95 which constitutes a part of the shaft 89.

Passing to Fig. 3, it will be observed that one end of a link 103 is pivoted to the arm 101 of the shaft 96, the other end of the 110 link being pivoted to the lower end of a lever 104 fulcrumed at 105 on a segment 106 carried by the frame 1, the lever having a latch mechanism 107 which co-operates with the segment. A flexible element 108 115 is connected with the latch mechanism 107 and is trained across a pulley 109 journaled on the lever 104. The flexible element 108 is extended around a direction-changing idler 110 mounted on the frame 1 and thence 120 is extended rearwardly to a point adjacent the seat 5, the standard 6 being provided with a cleat 111 upon which the free end of the flexible element 108 may be belayed.

One end of a link 112 is pivoted to the 125 lower end of the arm 95 which forms a part of the shaft 89, the other end of the link 112 being pivoted to the lower end of a lever 114 fulcrumed at 115 on a segment 116 carried by the frame 1. The lever 114 is pro- 130

vided with a latch mechanism 117 coöperating with the segment 116. The lever 114 is located close enough to the seat 5 so that the occupant of the seat can manipulate the lever 114 and its latch mechanism 117 without difficulty.

Comparing Fig. 4 with Fig. 3 it will be seen that a lever 118, disposed in an approximately horizontal position, is fulcrumed intermediate its ends, as shown at 119, on the frame 1 of the machine. The rear end of the lever 118 is accessible from the seat 5. Intermediate its ends, and upon one side of the fulcrum 119, the lever 118 is supplied with a depending eye or guide 120. At its end, and upon the opposite side of the fulcrum 119 from the guide 120, the lever 118 is provided with an eye or guide 121. When the lever 118 is in a neutral 20 position (to be defined hereinafter) the lever is engaged with a spring keeper 122 carried by the frame 1 and shown in detail in Fig. 5.

The numeral 123 denotes an actuating member in the form of a rigid rod extended 25 longitudinally of the machine and pivoted at one end to the lever 104 which, through the medium of the link 103 and the crank arm 101, participates in the movements of the shaft 96. The actuating member or rod 30 123 is mounted to tilt vertically and to slide longitudinally in the guide 121 which constitutes a part of the lever 118. The inner end of the rod 123 is supplied with a hook-shaped portion 124 carrying a roller 125.

35 The numeral 126 marks an actuating member, in the form of a rod, pivoted at one end to the lever 114 which, through the instrumentality of the link 112 and the arm 95, participates in the movement of the shaft 40 89. The rod 126 is adapted to move endwise and to tilt vertically in the guide 120 which forms a part of the lever 118. The inner end of the actuating member 126 is provided with a hook-shaped portion 127 carrying a 45 roller 153. The hook-shaped ends 127 and 124 of the actuating members 126 and 123, respectively, are adapted to engage, one at a time, with lateral projections 128 on the sprocket wheel 28 which, it is to be recalled, 50 is mounted on the main axle 24 and is driven by the engine 41. The actuating members 123 and 126 are raised and lowered, at their inner ends, by manipulating the lever 118, the function of the guides 120 and 121 being 55 clear and obvious. When the lever 118 is engaged with the keeper 122, as indicated in Fig. 5, the hook-shaped ends 127 and 124 of the respective actuating members 126 and 123 are disposed out of the orbit traversed 60 by the projections 128 on the sprocket wheel 28. This is the "neutral position" of the lever 118, hereinbefore mentioned.

The operation of the automatic plow lift.—
Let it be supposed that the vehicle is moving

in the direction of the arrow A of Fig. 2 and 65 that the plows 66 and 74 are in the ground. When the vehicle arrives at the end of the furrow, the operator disengages the lever 118 from the keeper 122 and swings the lever 70 downwardly on its fulcrum 119, thus lowering the guide 120 and the actuating member 126 until the hooked end 127 of the actuating member lies on the orbit of the projections 128 on the sprocket wheel 28. One of the projections 128, as it is carried in an 75 orbit in the sprocket wheel 28, moves the actuating member 126 lengthwise, the same sliding in the guide 120. After the actuating member 126 has moved lengthwise to a predetermined extent, the said projection 128 is 80 disengaged from the hook shaped end 127 on the actuating member, the roller 153 facilitating this operation. When the actuating member 126 moves endwise, the lever 118 is tilted, and the link 112 rocks the shaft 85 89 by means of the arm 95. When the shaft 89 is rocked, the arm 92 on the shaft 89 draws on the flexible element 94 and elevates the beam 73 and the plow 74. In a similar way, the arm 91 of the shaft 89 elevates the beam 62 and the plow 66 by means 90 of the flexible element 93. Thus, the plows 74 and 66 are raised out of the furrow, as the machine approaches the point where the furrow is to end.

When the lever 114 is swung as aforesaid, by the action of the member 126, the latch mechanism 117 on the lever 114 engages automatically with the segment 116, thereby 95 to hold the plows 74 and 66 elevated.

The operator restores the lever 118 to its neutral position, that is, in engagement with the keeper 122, the ends 124 and 127 of the actuating members 123 and 126 being disposed out of the path traversed by the projections 128 on the sprocket wheel 28. The vehicle may now be started back to plow a furrow in the direction of the arrow B of Fig. 2. In order to lower the plows 72 and 78, the operator draws on the flexible element 100 108, the same traveling over the idler 110 and the pulley 109. By this operation, the latch mechanism 107 on the lever 104 is released from the segment 106 thus setting the shaft 96 free for rotation. The arms 99 and 98 of the shaft 96 swing downwardly 105 under the weight of the beams 77 and 67, and the plows 72 and 78 enter the ground.

At the end of the furrow, plowed in the direction of the arrow B of Fig. 2, the lever 118 is manipulated to bring the hook end 124 on the actuating member 123 into the path of one of the projections 128 on the sprocket wheel 28. The lever 104 and the link 103 are actuated. The link 103 rocks the shaft 110 115 96 by way of the arm 101, the arm 97 effects an elevation of the plow beam 77, and the arm 98 effects an elevation of the plow beam

67, the plows 78 and 72 being lifted out of the ground. The actuating member 123 tilts the lever 104 and the latch mechanism 107 coöperates with the segment 106 to hold the 5 plows 72 and 78 elevated. When it is desired to lower the plows 74 and 66 to begin the furrow in the direction of the arrow A, this operation is brought about by tilting the lever 114, the latch mechanism 117 being 10 disengaged from the segment 116, a rotation of the shaft 89, and a downward swinging movement of the arms 92 and 91, together with the plow beams 73 and 62 taking place.

Modification.—In Figs. 6 and 7, the plow 15 beams are shown at 129. Levers 130 swing transversely of the plow beams and are fulcrumed at 131 on brackets 132 carried by the plow beams. The ends of a bar 133 are pivoted at 134 to the levers 130, the numeral 135 denoting any suitable means for 20 moving the bar 133 endwise. Disk plows 136 are journaled on the lower ends of the levers 130. It will be obvious that when the bar 133 is moved to the left (Figs. 6 and 25 7) the levers 130 will be tilted on their fulcra 131, thus to throw the disk plows 136 out of the furrow. When the furrow is begun, the engagement between the soil and the lower portions of the plow disks 136 will 30 carry the latter downwardly into working position in the soil.

Résumé.—The operation of the device has been set forth hereinbefore, step by step, but in conclusion it may be stated that the 35 operative connection between the engine 41 and the shaft 40 may be made and broken by manipulating the pedal 54. The direction of travel of the machine is reversed by operating the lever 47. The structure 40 is steered by means of the wheel 9. The lever 118 raises and lowers the actuating members 126 and 123 so that they may be operated by the projections 128 on the sprocket wheel 128. The plows are lowered 45 by means of the lever 114, on the one hand, and by means of the lever 104 on the other hand, the lever 104 being controlled by the flexible element 108 which is extended rearwardly to a point adjacent the seat 5. The 50 inner plow beams 73 and 77 may be adjusted vertically at their points of pivotal support by swinging the levers 85 on their fulcra 86.

Rings 200 may be applied to the side faces 55 of the wheels 75 and 76, the rings comprising parts 201 and 202, held in place by securing elements 203. The rings 200 tend to offset side draft. They are removed when the device is being moved from place to 60 place along the highway.

It will be understood that any of the gears hereinbefore mentioned may be made to run in oil. This is a detail lying within the skill of a mechanic, and unworthy of specific 65 delineation.

Having thus described the invention, what is claimed is:—

1. In a device of the class described, a frame; transverse shafts journaled on the frame and having arms; first levers under 70 the control of an operator and fulcrumed on the frame; links connecting the levers with the arms; a second lever fulcrumed on the frame; actuating members pivoted to the first levers and movably supported on the 75 second lever; an axle journaled on the frame; a ground wheel carried by the axle; an eccentric element carried by the axle and movable in an orbit, the second lever constituting means for bringing the actuating members, one at a time, into the orbit of the eccentric element; beams pivoted to the frame; opposed plows carried by the beams; means for connecting each beam with one of the transverse shafts to raise 80 the plows when the shafts are rotated by the actuating members; and latch mechanisms controlling the first levers, the latch mechanisms acting automatically to hold the plows elevated, and being releasable by 85 an operator to permit a lowering of the plows.

2. A device constructed in accordance with claim 1, and further characterized by the provision of means for engaging the 90 second lever to hold the second lever and both of the actuating members out of the orbit of the eccentric element.

3. In a device of the class described, a frame; transverse shafts journaled on the 100 frame and having arms; first levers under the control of an operator and fulcrumed on the frame; links connecting the levers with the arms; a second lever fulcrumed on the frame; actuating members pivoted to 105 the first levers and movably supported on the second lever; a rotatable member journaled on the frame; means for rotating said member; an eccentric element carried by the rotatable member and movable in an 110 orbit, the second lever constituting means for bringing the actuating members one at a time into the orbit of the eccentric element; beams pivoted to the frame; opposed 115 plows carried by the beams; means for connecting each beam with one of the transverse shafts to raise the plows when the shafts are rotated by the actuating member; and latch mechanisms controlling the first levers, the latch mechanisms acting automatically to hold the plows elevated, and being releasable by an operator to permit 120 a lowering of the plows.

4. In a device of the class described, a frame; transverse shafts journaled on the 125 frame; first levers under the control of an operator and fulcrumed on the frame; means for connecting the levers with the shafts; a second lever fulcrumed on the frame; actuating members pivoted to the first levers 130

and movably supported on the second lever; an axle journaled on the frame; a ground wheel carried by the axle; an eccentric element carried by the axle and movable in an orbit, the second lever constituting means for bringing the actuating members, one at a time into the orbit of the eccentric element; beams pivoted to the frame; opposed plows carried by the beams; means for connecting each beam with one of the transverse shafts to raise the plows when the shafts are rotated by the actuating members; and latch mechanisms controlling the first levers, the latch mechanisms acting automatically to hold the plows elevated, and being releasable by an operator to permit a lowering of the plows.

5. In a device of the class described; a frame; transverse shafts journaled on the frame and having arms; levers under the control of an operator and fulcrumed on the frame; links connecting the levers with the arms; actuating members pivoted to the first levers; an axle journaled on the frame; a ground wheel carried by the axle; an eccentric element carried by the axle and movable in an orbit; means for bringing the actuating members one at a time into the orbit of the eccentric element; beams pivoted to the frame; opposed plows carried by the beams; means for connecting each beam with one of the transverse shafts to raise the plows when the shafts are rotated by the actuating members; and latch mechanisms controlling the first levers, the latch mechanisms acting automatically to hold the plows elevated, and being releasable by an operator to permit a lowering of the plows.

6. In a device of the class described, a frame; transverse shafts journaled on the frame; first levers under the control of an

operator and fulcrumed on the frame; means for connecting the first levers with the shafts; an axle journaled on the frame; a ground wheel carried by the axle; an eccentric element carried by the axle and movable in an orbit; actuating members pivoted to the levers; means for moving the actuating members one at a time into the orbit described by the eccentric element; beams pivoted to the frame; opposed plows carried by the beams; means for connecting each beam with one of the transverse shafts to raise the plows when the shafts are rotated by the actuating members; and means for controlling the movement of the first levers.

7. In a device of the class described, a frame; a rotatable member journaled on the frame and having an eccentric element movable in an orbit; actuating members; means supporting both actuating members, for moving the actuating members in opposite directions, one at a time, and for bringing them selectively into the orbit of the eccentric element; plows pivotally supported on the frame; shafts journaled on the frame; means for connecting the shafts with the plows; connections between the actuating members and the shafts, whereby the shafts will be rotated and the plows raised by the actuating members; and means assembled with the connections for holding the plows elevated.

In testimony that I claim the foregoing as my own, I have hereto affixed my signature in the presence of two witnesses.

OTTO HECHT.

Witnesses:

KASPAR KILIAN,
CARL BRIETZKE.
